UNITED STATES PATENT OFFICE.

ALBERT J. HUNTOON, OF KANSAS CITY, MISSOURI.

DESIGN FOR A SPINNING TOP.

SPECIFICATION forming part of Design No. 21,753, dated August 2, 1892.

Application filed June 29, 1892. Serial No. 438,450. Term of patent 7 years.

To all whom it may concern:

Be it known that I, ALBERT J. HUNTOON, of Kansas City, in the county of Jackson and State of Missouri, have invented and produced 5 a new and original Design for a Spinning Top, of which the following is a full, clear, and exact description.

The design consists in the novel configuration and ornamentation shown. Thus the lines 10 of the body at the center present the form of a hexagonal band, the faces *a* being embellished to simulate the sides of dice. Above and below the central hexagonal band the body is rounded, as at *b c*, the lines of the 15 said rounded portions terminating in central neck-like projections *b' c'*. At the bottom,

beyond the neck-like projection *b'*, the lines terminate in a pointed knob-like figure *b²*. At the top the lines of the ornamental handle *D* depart from the neck-like figure *c'*, rising in the form of a cylindrical figure *d*, and from the upper end of such cylindrical figure the lines rise in the form of a second and smaller cylindrical figure *d'*, the whole being surmounted by a rounded figure *d²*. 20 25

I claim—

The design for a spinning top, herein shown and described.

ALBERT J. HUNTOON.
